APPARATUS FOR STOPPING LOST CIRCULATION

Abraham J. Teplitz, Penn Township, Allegheny County, Pa., assignor to Gulf Research & Development Company, Pittsburgh, Pa., a corporation of Delaware

Application December 30, 1954, Serial No. 478,748

2 Claims. (Cl. 166—162)

This invention relates to improved method and means for stopping lost circulation of drilling fluids and refers particularly to apparatus containing improvements specifically adapted to stopping such lost circulation.

A major factor in the high cost of drilling many wells is the lost circulation of drilling fluids or mud into openings or thief zones in formations penetrated by the borehole; such lost circulation, in addition to involving loss of costly materials and expensive rig time can result in stuck drill pipes, a lost hole, blow-out, or abandonment. When a condition of lost circulation once occurs, it is necessary, generally, to seal off the thief zone before continuing the drilling operation. It has been the practice to introduce sealing material, usually a time-setting material such as cement, in the drilling fluid in the drill pipe and then pump it through the drill pipe and into the formation to plug the openings in the loss zone. In this method, a large volume of drilling mud must be lost in the course of being displaced into the loss zone ahead of the sealing material, and there is, in addition, no assurance that the sealing material will set up in the openings to the loss zone and thus great quantities of sealing material can be lost also. If too much displacing fluid is used, the sealing material will be driven too far back in the loss zone to be effective; if too little is used, the sealing material will not reach the zone. Furthermore, the sealing material may become diluted with drilling fluid in the course of being pumped to the loss zone and then fail to set up properly.

An object of my invention is to provide means whereby sealing material can be delivered in concentrated form to the point of lost circulation without incurring additional loss of drilling fluid and can be fed to openings at a moderate pressure which will neither create more openings in the loss zones nor force the sealing material back into the formation where it is unable to form an effective seal.

Briefly stated, my invention consists essentially of means for delivering a concentrated sealing material to a loss zone, the said means consisting essentially of a bailer, which bailer is closed at the bottom by a frangible disk to which is affixed a powder cap or its equivalent that, upon exploding, will destroy the bottom closure of the bailer and allow the sealing material to flow out of the bailer into the surrounding periphery of the thief formation.

The bailer, which is supported on a cable for raising and lowering it in the borehole to a predetermined point therein, can consist more specifically of an elongated, hollow, cylindrical housing of which at least the bottom end is closed, a frangible disk effecting a destructible bottom closure, a mildly explosive cartridge or cap placed against the disk, a sleeve or threadedly attached assembly thereof for holding the disk against the housing, and wires connecting the cartridge to means operable from the ground surface for triggering the cartridge to destroy the disk. The bailer, or a part thereof, can be constructed of a drillable material such as a plastic, or a suitable metal

2

or alloy, so that it will not be necessary to fish for and remove the bailer in case it becomes lodged in the borehole. The bailer is closed at the top and includes self-propelling means for pressing sealing material into the openings.

In the accompanying drawings, which are supplied for the purpose of illustrating preferred embodiments of this invention,

Fig. 1 is a vertical sectional view of a bailer having a single means for destroying the frangible bottom of the bailer and one arrangement for energizing this means, and

Fig. 2 is a vertical sectional view of an embodiment specifically adapted to providing self-generated means for delivering lost-circulation sealing material into a loss formation.

Referring now to Fig. 1, the bailer shown therein consists of an upper housing 10, which can be open at the top 11, and a lower assembly 12, connected by screw threads to the upper housing and having a frangible-disk bottom 13.

The frangible disk 13 is held firmly between rubber gaskets 14 and by a sleeve 15 threadedly connected to a cylindrical section 16 which in turn is connected to the upper housing 10. A bail or handle 17 is attached to the sleeve 15 for the purpose of grasping the lower assembly 12, consisting of the sleeve 15 and cylindrical section 16, and screwing them to the upper housing 10. The section 16, sleeve 15, and handle 17 are constructed of drillable materials. A blasting cap 18 is placed on the frangible disk 13 in such position that when it is exploded the frangible disk will be shattered. A thin drillable metal clip 19 is placed on the blasting cap 18, extends to the edges of the disk, and is held firmly in place between the upper gasket 14 and the bottom rim of cylindrical section 16.

Wires 20 and 20a lead from the blasting cap 18 to a bail or handle 21 having a connector 22 where the wires are conventionally connected into cable 23. Cable 23 constitutes the suspending means by which the bailer is lowered into a borehole. Alternatively one of the wires 20 and 20a can be attached to hold-down strip 19, and be grounded through the strip 19 and the cylindrical section 16, housing 10, bail 21, and suspending cable 23.

The bailer can be filled with substantially any kind of free-flowing lost-circulation sealing material and is especially suitable for carrying large-sized material which cannot be pumped into the borehole. When the bailer is open at the top, the structure of the bailer is not subjected to pressures within the borehole which might cause its premature collapse. Being open, however, a bailer of this type is best suited to the delivery of sealing material having a higher density than the employed drilling fluid through which the bailer is lowered. In case mixing of the sealing material and the drilling fluid must be completely prevented, a top can easily be fitted to the bailer and this top (not shown) can be yieldably or slidably fitted to the bailer so that internal and external pressures on it will still remain substantially the same.

When a condition of lost circulation occurs and the introduction of drilling fluid into the borehole and its recirculation has been discontinued, the drilling fluid in the borehole will become balanced against the pressure in the thief zone and will stand at some level in the borehole. When the bailer, which may be for example 40 to 80 feet long, is introduced into the borehole it will displace part of the column of drilling fluid causing more fluid to flow into the loss formation. When the bailer has been placed near the point of loss and the frangible disk has been shattered, the sealing material then flows into the openings in the thief zone. This occurs as a result of

its weight, when the density of the sealing material is greater than that of the drilling fluid, or, otherwise, it can be moved into the formation under the mild pressure of an additional weight of drilling fluid added to the top of the column of fluid.

Referring now more particularly to Fig. 2 in which parts the same as those in Fig. 1 are indicated by the same reference characters, a spool piece 15 is screwed onto a lower cylindrical section 16 by the use of the bail or handle 17 whereby the frangible disk 13 is firmly held between the spool 15 and section 16 and against the gaskets 14. The frangible disk bears a blasting cap 18 held down by clip 19 and the cap 18 is connected to wires 20 and 20a which transmit the current to explode the cap. The upper section 24 of this bailer which is threadedly connected to lower section 16 is closed by a top 25; this top is fitted with a valved inlet 26. The upper section 24 is substantially longer than the upper housing 10 of the bailer of Fig. 1 in order to provide a gas space 27. The housing 24 is provided with a bail 28 and connector 29. Beneath the bail 28 and resting on the top 25 is a housing 30 in which can be placed a dry cell battery 31. A suspending cable 23 attached to the connector 29, is employed for lowering the bailer into a borehole. Mounted on the cable 23 at a point near the connector 29 are two separated contact points 32 and 33, the lower one of which is rigidly attached to the cable 23. The upper contact point 32 is slidably mounted concentrically to the cable 23 and is vertically supported by a slight non-conductive spring 34 which separates it from contact point 33. The spring can fit into convex sections 32a and 33a so that when the spring 34 is compressed, points 32 and 33 will make contact with each other.

A go-devil 35 can be slipped on the cable 23 at the surface and will slide down the cable and strike slideable point 32. This will close the circuit which consists of wire 36 leading from battery 31 to contact point 33 and wire 20 leading from contact point 32 to the blasting cap 18. Wire 20a leads from the battery 31 to the blasting cap 18.

In employing the bailer of Fig. 2, the holdown clip, wires, and blasting cap are first put in place and spool 15 is screwed onto section 16 to hold the frangible disk 13 in position. The wires 20 and 20a are strung through the section 24. The bailer is then partially filled with a sealing material, this being most conveniently accomplished by lowering the bailer into the borehole and holding it therein with slips at a level such that the top of the bailer can be reached for filling. After the bailer is partially filled with sealing material, the top 25 is screwed into position and the wires are connected to the cable 23. A gas, e. g., carbon dioxide or nitrogen, is pumped into the bailer through the valved inlet 26 until a mild pressure of gas is established within the bailer. This gas pressure, after the disk 13 is destroyed, will provide a mild driving force to gently push the sealing material from the bailer into the loss zone. This embodiment is especially useful when the sealing material is of lower specific gravity than the drilling fluid.

Several modifications, in addition to those shown in Figs. 1 and 2, of means for shattering the frangible disk 13 can be employed. A go-devil can be caused to trigger a cocked spring attached to a pointed rod which, when the spring is released, will penetrate and shatter the frangible disk. Other means can include thermal shock or melting, such as would be accomplished by energizing a heating coil placed in a disk of low melting point.

Some of the sealing materials that can be used in the 10 bailer of my invention include cement, comminuted nut shells, cottonseed hulls, and fibrous materials. Hydratable sealing materials such as bentonite can also be employed, the latter preferably in admixture with a lubricant. In addition to the advantage of avoiding dilution of the sealing material, my method and means for sealing loss formations also has the advantage that particles of larger size than that of particles which can pass through pumps or the ports in the drill bit can easily be employed.

Having described my invention, I claim:

1. Apparatus for delivering a flowable material to a predetermined point in a borehole of a well comprising a hollow cylindrical housing, a frangible disk closing the lower end of the housing, an explosive charge adjacent the frangible disk adapted to rupture the disk upon detonation, means operable from the well head for detonating the explosive charge, a gas tight top closing the upper end of the housing, flowable material in the lower portion of the housing, a compressed gas within the housing above the flowable material and adapted to force the flowable material from the housing on rupture of the disk, and a supporting cable connected to the housing and extending to the well head for suspending the housing at the desired height in the well.

2. Apparatus as set forth in claim 1 in which a valved 35 inlet opens into the housing for introduction of the compressed gas into the housing.
